UNITED STATES PATENT OFFICE

124,117

DESIGN FOR A DRESS ENSEMBLE

William Skolnick, New York, N. Y.

Application September 26, 1940, Serial No. 95,374

Term of patent 3½ years

To all whom it may concern:

Be it known that I, William Skolnick, a citizen of the United States of America, residing in the city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary front view of the dress member.

Fig. 4 is a rear view of Fig. 3.

The characteristic feature of my design for a dress ensemble resides in the specific jacket member having buttons arranged along the curved front seams, a contrastingly colored collar, and a peplum back, all as shown.

I claim:

The ornamental design for a dress ensemble, as shown and described.

WILLIAM SKOLNICK.
